No. 769,723.

PATENTED SEPT. 13, 1904.

T. WILKINS.
KNIFE SHARPENING DEVICE.
APPLICATION FILED DEC. 31, 1903.

NO MODEL.

UNITED STATES PATENT OFFICE.

THEODORE WILKINS, OF NEW YORK, N. Y.

KNIFE-SHARPENING DEVICE.

SPECIFICATION forming part of Letters Patent No. 769,723, dated September 13, 1904.

Application filed December 31, 1903. Serial No. 187,308. (No model.)

To all whom it may concern:

Be it known that I, THEODORE WILKINS, a citizen of the United States, residing at New York, in the county of New York and State of New York, have invented certain new and useful Improvements in Knife-Sharpening Devices, of which the following is a specification, such as will enable those skilled in the art to which it appertains to make and use the same.

10 The object of this invention is to provide an improved knife-sharpening device which may be held in the hand or secured to a table or other support and by means of which a knife of any kind or class may be easily and quickly 15 sharpened and which is also constructed so as to control the angle at which the edge of the knife will be held to the stone or other sharpening medium.

20 The invention is fully disclosed in the following specification, of which the accompanying drawings form a part, in which the separate parts of my invention are designated by suitable reference characters in each of the views, and in which—

25 Figure 1 is a side view of one form of my improved knife-sharpening device and showing the same connected with a table or other support and held in an upright position; Fig. 2, a transverse section of the sharpening device on the line 2 2 of Fig. 1; Fig. 3, a view, 30 similar to Fig. 1, of a modified form of the knife-sharpener; Fig. 4, a cross-section thereof on the line 4 4 of Fig. 3; and Fig. 5, a view similar to Fig. 4, but showing another modification.

35 In the practice of my invention I provide two head or end pieces *a*, between which a stone or similar device *b* is placed, and the head or end pieces *a* are preferably provided with rims, 40 flanges, or other holders *a*², within which the ends of the stone are placed. The head or end pieces *a* in the form of construction shown in Figs. 1 and 2 are provided with radially-arranged members *a*³, four of which are shown 45 and through which are passed rods *c*, four of which are employed when the stone *b* is rectangular in form. The rods *c* are arranged at different distances from the stone, as shown

in Figs. 1 and 2, and in practice the blade of the knife to be sharpened is inserted between 50 one of the rods *c* and the stone and moved back and forth over the stone in the usual manner, and the rods *c*, between which and the stone the blade of the knife is inserted, will fix the angle at which the edge of the blade of 55 the knife presses on the stone, and by reason of the fact that the rods *c* are placed at different distances from the stone this angle may be regulated as desired.

60 In the form of construction shown in Figs. 1 and 2 is secured to one of the head or end pieces *a* in any desired manner a clamp *d*, by means of which the knife-sharpener may be secured to a table or any other support.

65 In Figs. 3 and 4 I have shown a modification in which the rods *c*² are adjustable toward and from the stone, this adjustment being accomplished by means of radial slots *e* in the members *a*⁴, through which the rods *c*² are passed, and said rods are provided at one end 70 with a thumb-nut *f*, and by means of this construction the rods *c*² may be adjusted toward and from the stone, and the angle at which the edge of the blade of a knife to be sharpened is held on the stone may be thus easily 75 regulated, and one or more of the rods *c*² may be made adjustable and the other stationary.

80 It will be understood that the stone *b* may be of any desired shape in cross-section; but when provided with flat sides or faces the number of rods employed will equal the said 85 sides or faces, and in Fig. 5 I have shown another modification in which the stone *b* and the head or end pieces *a* are also circular in form, and three of the rods *c* are employed, said rods being arranged at different distances from the stone.

85 My improved knife-sharpener is simple in construction and comparatively inexpensive and may be conveniently used wherever devices of this kind are required.

90 Having fully described my invention, what I claim as new, and desire to secure by Letters Patent, is—

95 1. A knife-sharpener, comprising two end or head portions, a stone placed between the

same, and a plurality of rods by which said head or end portions are connected, said rods being arranged at a predetermined distance from the stone, substantially as shown and described.

2. A knife-sharpener, comprising two end or head portions, a stone placed between the same, and a plurality of rods by which said head or end portions are connected, said rods being arranged at a predetermined distance

from the stone and being radially adjustable, substantially as shown and described.

In testimony that I claim the foregoing as my invention I have signed my name, in presence of the subscribing witnesses, this 30th day of December, 1903.

THEODORE WILKINS.

Witnesses:

F. A. STEWART,
C. E. MULREANY.
